UNITED STATES PATENT OFFICE.

GEORGE A. HOLLIER, OF SIOUX FALLS, SOUTH DAKOTA.

DESIGN FOR A RING.

49,432.

Specification for Design.

Patented July 25, 1916.

Application filed June 1, 1916. Serial No. 101,186. Term of patent 3½ years.

To all whom it may concern:

Be it known that I, GEORGE A. HOLLIER, a citizen of the United States, residing at Sioux Falls, in the county of Minnehaha and State of South Dakota, have invented a new, original, and ornamental Design for Rings, of which the following is a specification, reference being had to the accompanying drawing, forming a part thereof.

Figure 1 is a front elevation of a ring, showing my new design. Fig. 2 is a perspective view of the same.

I claim:

The ornamental design for a ring, as shown.

GEORGE A. HOLLIER.
